[57] ABSTRACT

The present invention relates to benzonaphthyridine derivatives of the formula,

wherein R is dichloromethyl, cycloalkyl of 3 to 6 carbon atoms, or alkenyl of 2 to 5 carbon atoms, useful as blood platelet aggregation inhibitors.

7 Claims, No Drawings

CIS-6-(ACYLAMINOPHENYL)-8,9-DIMETHOXY-2-METHYL-1,2,3,4,4A, 10B-HEXAHYDRO-BENZO [C]-[1,6] NAPHTHYRIDINE

IMPROVEMENTS IN OR RELATING TO ORGANIC COMPOUNDS

The present invention relates to benzonaphthyridine derivatives.

In accordance with the invention there are provided compounds of formula I,

I

wherein R is dichloromethyl, cycloalkyl of 3 to 6 carbon atoms or alkenyl of 2 to 5 carbon atoms.

When the radical R is cycloalkyl of 3 to 6 carbon atoms, this especially contains 5 or 6 carbon atoms and may, for example, signify cyclohexyl.

When R is alkenyl of 2 to 5 carbon atoms, this radical especially signifies vinyl, or vinyl wherein 1 to 3 hydrogen atoms are substituted by methyl groups.

The radical R-CONH- is preferably in the 4 position of the phenyl radical to which it is bound.

Further, in accordance with the invention, a compound of formula I may be obtained by a process comprising acylating compounds of formula II,

II

The acylation in accordance with the invention of compounds of formula II with carboxylic acid halides or anhydrides is conveniently effected in an inert organic solvent such as pyridine or acetonitrile. This acylation is conveniently effected at a reaction temperature between room temperature and the boiling temperature of the reaction mixture.

The compounds of formula II are known or may be produced in accordance with known processes or in a manner analogous to known processes.

Acid addition salt forms of compounds of formula I may be produced from the free base forms in conventional manner and vice versa. Suitable acids for acid addition salt formation include inorganic acids such as hydrochloric acid, hydrobromic acid, sulphuric acid and organic acids such as tartaric acid, benzenesulphonic acid and acetic acid.

In the following non-limitative Examples all temperatures are indicated in degrees Centigrade and are uncorrected.

EXAMPLE 1

Cis-6-(4-dichloroacetylaminophenyl)-8,9-dimethoxy-2-methyl-1,2,3,4,4a,10b-hexahydro-benzo[c][1,6]naphthyridine

2 g of 6-(4-aminophenyl)-8,9-dimethoxy-2-methyl-1,2,3,4,4a,10b-hexahydro-benzo[c][1,6]naphthyridine, 10 ml of pyridine and 6 g of dichloroacetyl chloride are heated to 60° for 2 hours. 10 ml of water are subsequently added to the reaction mixture and this is evaporated to dryness in a vacuum. The resulting oily residue is dissolved in ethanol and a slight excess of hydrochloric acid in ethanol is added, whereby the title compound crystallizes in dihydrochloride form as yellowish prisms having a melting point of 107°-111°.

EXAMPLE 2

Cis-6-(4-acryloylaminophenyl)-8,9-dimethoxy-2-methyl-1,2,3,4,4a,10b-hexahydrobenzo[c][1,6]naphthyridine

The title compound is obtained in a manner analogous to that described in Example 1 by acylation of 6-(4-aminophenyl)-8,9-dimethoxy-2-methyl-1,2,3,4,4a,10b-hexahydro-benzo[c][1,6]naphthyridine with acrylic acid chloride. The crude product obtained is worked up by evaporating the mixture to dryness and adding water to the residue. The reaction mixture is made alkaline with potassium carbonate and extracted with methylene chloride. The solution is concentrated by evaporation and the crude product is dissolved in ethanol, hydrochloric acid in ethanol is added to the solution and this is evaporated to dryness in a vacuum. Upon adding acetone, the dihydrochloride form of the title compound (melting point 243°) crystallizes.

EXAMPLE 3

Cis-6-(4-cyclohexylcarboxamidophenyl)-8,9-dimethoxy-2-methyl-1,2,3,4,4a,10b-hexahydro-benzo[c][1,6]naphthyridine

3.5 g of 6-(4-aminophenyl)-8,9-dimethoxy-2-methyl-1,2,3,4,4a,10b-hexahydro-benzo[c][1,6]naphthyridine are dissolved in 40 ml of pyridine and after the addition of 2.3 g of cyclohexylcarboxylic acid chloride the reaction solution is allowed to stand over night at room temperature. After working up and purifying in a manner analogous to that described in Example 2, the dihydrochloride form of the title compound, having a melting point of 236°-240°, is obtained.

The compounds of formula I have not been described in the literature.

The compounds of formula I are useful because they possess pharmacological activity in animals. In particular, the compounds of formula I are useful as blood platelet aggregation inhibitor agents for example in the treatment and prophylaxis of thrombosis and for improving micro-circulation in animals, as indicated by an inhibition of blood platelet aggregation induced in vitro by adenosine diphosphate in rabbit platelet-rich plasma in accordance with the turbidimetric method of Born at a concentration of from about 20 to about 30 µg/ml of the compounds.

For the above mentioned use the dosage will, of course, vary depending on the compound employed, mode of administration and therapy desired. However, in general, satisfactory results are obtained when ad-

ministered at a daily dosage of from 0.1 mg to about 10 mg per kg animal body weight, conveniently given in divided doses two to four times a day or in sustained release form. For the larger mammal, the total daily dosage is in the range from about 10 to about 400mg, and dosage forms suitable for oral administration comprise from about 2 mg to about 200 mg of the compounds admixed with a solid or liquid pharmaceutical carrier or diluent.

The compounds of formula I may be administered in pharmaceutically acceptable acid addition salt form. Such acid addition salt forms exhibit the same order of activity as the free base forms and readily prepared in conventional manner. Representative acids for addition salt formation include organic acids such as maleic, fumaric and tartaric acids and mineral acids such as hydrochloric, hydrobromic and sulphuric acids. A pharmaceutical composition may comprise a compound of formula I, in free base form or in pharmaceutically acceptable acid addition salt form, in association with a pharmaceutical carrier or diluent. Such compositions conveniently contain more than 1% by weight of the compound of formula I and may be prepared by conventional techniques to be in conventional forms, for example, capsules, tablets, suppositories, dispersible powders, syrups, elixirs, suspensions or solutions, for enteral or parenteral administration. Suitable pharmaceutical diluents or carriers include, for example, water, alcohols, natural or hardened oils and waxes, calcium and sodium carbonates, calcium phosphate, kaolin, talc and lactose as well as suitable preserving agents, such as ethyl-p-hydroxybenzoate, suspending agents such as methyl cellulose, tragacanth and sodium alginate, wetting agents such as lecithin, polyoxyethylene stearate and polyoxyethylene sorbitan monooleate, granulating and disintegrating agents such as starch and alginic acid, binding agents such as starch, gelatin and acacia, and lubricating agents such as magnesium stearate, stearic acid and talc, in order to provide an elegant and palatable pharmaceutical preparation. Compositions in tablet form may be coated by

conventional techniques to delay disintegration of the tablet and absorption of the active ingredient in the gastrointestinal tract and thereby provide sustained action over a long period.

The preferred compositions from the standpoint of ease of administration are solid compositions, particularly solid-filled gelatin capsules and tablets.

We claim:

1. A compound of the formula,

wherein R is dichloromethyl, cycloalkyl of 3 to 6 carbon atoms or alkenyl of 2 to 5 carbon atoms, or a pharmaceutically acceptable acid addition salt thereof.

2. A compound of claim 1 wherein R is dichloroalkyl.

3. A compound of claim 1 wherein R is cycloalkyl.

4. A compound of claim 1 wherein R is alkenyl.

5. The compound of claim 1, which is

Cis-6-(4-dichloroacetylaminophenyl)-8,9-dimethoxy-2-methyl-1,2,3,4,4a,10b-hexahydrobenzo[c]-[1,6]naphthyridine.

6. The compound of claim 1, which is

Cis-6-(4-acryloylaminophenyl)-8,9-dimethoxy-2-methyl-1,2,3,4,4a,10b-hexahydrobenzo[c]-[1,6]naphthyridine.

7. The compound of claim 1, which is

Cis-6-(4-cyclohexylcarboxymidophenyl)-8,9-dimethoxy-2-methyl-1,2,3,4,4a,10b-hexahydrobenzo[c]-[1,6]naphthyridine.
